UNITED STATES PATENT OFFICE.

EARL G. WATROUS, OF CHICAGO, ILLINOIS.

BALL-COCK VALVE.

No. 901,571.

Specification of Letters Patent.

Patented Oct. 20, 1908.

Application filed April 15, 1901. Serial No. 55,938.

To all whom it may concern:

Be it known that I, EARL G. WATROUS, a citizen of the United States of America, residing at Chicago, in the county of Cook and State of Illinois, have invented a certain new and useful Improvement in Ball-Cock Valves, of which the following is a description, reference being had to the accompanying drawings, forming part of this specification.

My invention has for its object the simplification of construction, lessening of cost and increase of efficiency of ball cock valves commonly used in the flushing tanks of water closets; and its novelty will be hereinafter set forth and particularly pointed out in the claims.

In the accompanying drawings Figure 1 is a sectional view of a part of a flushing tank equipped with my improved valve; Fig. 2 a vertical section of the valve in closed position; Fig. 3 a corresponding view with the valve in open position; Fig. 4 a horizontal section through the cap or head of the valve casing; Fig. 5 a section detail on the line 5—5 of Fig. 4; Fig. 6 a vertical section of the valve with the ball supporting arm swung to position to release the valve stem, and with the coupling removed from the lower end of the valve casing to permit the removal of the valve; Fig. 7 a cross section on the line 7—7 of Fig. 2; Fig. 8 a perspective view of the valve itself, removed from the casing; Fig. 9 a vertical section of a modified form of the valve employing a removable metal valve seat; Fig. 10 a perspective view of such removable seat; Fig. 11 a perspective view of my improved valve modified to adapt it to be secured to the upper edge of the flushing tank; and Fig. 12 a vertical section of the valve shown in Fig. 9.

The same letters of reference are used to indicate identical parts in the several views.

The valve casing shown in Figs. 1 to 9 consists of a tubular body A provided at its upper end with an integral horizontal cap or hood B to direct the water laterally into the tank and incidentally to form a bearing for one end of the valve-operating rod C to whose opposite free end is secured the usual ball or float D. The tubular body of the valve casing is adapted to be passed downward through a circular hole in the bottom of the flushing tank E, and is provided at its upper end with a circular flange F adapted to rest upon said bottom. The body of the valve

casing A is exteriorly threaded for a considerable portion of its length, and a nut G mounted upon this threaded portion and screwed up tightly against the under surface 60 of the bottom of the tank E clamps the flange F against the upper surface thereof and serves to firmly secure the valve casing in position.

Longitudinally disposed in the valve casting A is the valve stem H carrying the valve I at its lower end, and at its upper end extending into the cap or hood B and provided with a hook or recess a to engage the crank of the valve operating rod C, as shown. The 70 valve end of this rod is bent at right angles to the body of the rod and passes through apertures formed for it in the opposite sides of the cap or hood B, Fig. 4. The middle portion of this angular bent end of the rod C, 75 within the hood B, is bent to form a crank C' which is connected with the upper end of the valve stem H by the hook a of the latter. When the outer end of the rod C is elevated the crank will force the valve stem downward, as in Fig. 2, and when the outer end of the rod is allowed to fall the crank will lift the valve stem, as in Fig. 3. The valve is in the present instance of the shape shown in Fig. 8, and provided, near its upper and lower ends, with side flanges or guide ribs b adapted to fit and travel in corresponding guide ways c formed upon the interior of the tubular valve casing A near the upper and lower ends of the latter, Fig. 7. The cup 80 shaped valve I, Fig. 2, is formed upon the lower end of the stem H, and when the latter is forced downward seats itself against a rubber seat J upon the upper end of the pipe connection or tailpiece K which is secured to 85 the lower end of the valve casing A by means of the coupling nut L.

As will be understood from the foregoing description, when the ball or float D is permitted to drop, by the descent of the water 100 in the tank at the flushing of the closet, it will lift the valve I from its seat and permit the water from the supply pipe connected to the lower end of the valve casing to pass upward through the valve casing into the tank, 105 and as the water rises in the tank and lifts the float the valve will be forced downward to its seat again and the supply of water cut off.

To permit the insertion of the bent end of 110 the rod C and its crank C' into the cap or hood of the valve casing, in assembling the

parts, and its withdrawal in taking them apart, the inner surface of one of the side walls of said cap is cut away or cored out immediately beneath the hole through which 5 the end of the rod C is inserted, as shown at d in Fig. 5. With this provision, when the rod C is swung to vertical position the space d will permit the bent end of the rod and its crank to be withdrawn from the cap B sufficiently to disengage the free end of the 10 crank from its bearing in the opposite side wall of the cap, whereupon the rod C may be entirely withdrawn and disconnected from the cap.

15 For the purpose of locking the crank end of the rod C in its bearing in the cap B and preventing its accidental displacement while in operative position, I provide upon the inner surfaces of the opposite side walls of 20 the cap B, immediately in rear of the apertures in which the crank C' has its bearings, two locking lugs e, e', Fig. 5, whose forward surfaces are curved to fit the rear side of the crank C', Fig. 4, and while permitting it to 25 turn freely in its bearings, serve to lock it from lateral displacement unless the rod is swung upward to or beyond vertical position and the crank thereby swung downward and forward out of the vertical plane of the lugs, 30 whereupon it is free to be withdrawn from the cap as before explained.

As will be understood from the foregoing, 35 as long as the rod C remains anywhere within the range of its operative position, Figs. 1, 2 and 3, it is securely locked in its bearings in the valve casing and cannot become accidentally displaced therefrom; while by 40 swinging it upward beyond the range of its operative position it may be readily removed.

Only one lug, at the side of the casing at 45 which the crank of the rod is inserted, is essential for the locking operation above described, but I prefer to employ the two lugs, e and e', upon the opposite sides of the casing, as described.

The valve is simple in construction and composed of few parts, and consequently may be cheaply made. The valve casing 50 proper is a simple tubular casting, exteriorly threaded, and constitutes practically nothing more than the mere shank of the usual ball cock valves, employed for securing them in the bottom of the tank. The valve stem and valve are likewise a single 55 simple casting, while the operating rod C is composed of a single piece of heavy wire having the float secured to its free end, and at its opposite end directly connected to the 60 valve stem, with no intermediate parts. The length of the operating rod C relatively to the crank C' affords a powerful leverage for forcing the valve downward against its seat when the free end of the rod is elevated 65 by the rising of the water in the tank, and

therefore insures the prompt and firm seating of the valve against high water pressures. The parts may be readily assembled, and be readily taken apart even without removing the valve casing from the tank. Thus if it 70 be desired to gain access to the interior of the valve casing, to replace a worn valve seat or put in a new valve, it is only necessary to unscrew the nut L and swing the pipe connection K to one side, whereupon 75 the valve seat may be readily removed and replaced with a new one, while if the valve itself is to be removed it is simply necessary to swing the operating rod C over to the position indicated in Fig. 6, whereupon the 80 crank C' will be disengaged from the valve stem and the latter left free to be withdrawn from the casing. Upon inserting a new valve to the position shown in Fig. 6 and 85 swinging the rod C back to operative position its crank C' will engage the upper end of the new valve stem, as in Fig. 2, and it will then be simply necessary to swing the pipe connection K back into line with the 90 valve casing and recouple the parts with the nut L.

For the foregoing and other reasons my improved valve is superior to any valve of this character with which I am acquainted, 95 in simplicity, in economy in construction, in efficiency, and in facility for assemblage and repairs.

In Figs. 9 and 10 I have illustrated a modified form of my valve in which the valve upon the lower end of the stem H consists of 100 a rubber or other flexible disk I' adapted to seat against a removable seat M of metal or other hard material which fits within the lower end of the casing A and rests against an annular shoulder formed therein to receive it. A rubber gasket N is interposed between the under side of this removable seat and the upper end of the tail-piece K within the coupling nut L, and the seat M is held in position when the nut is tightened up. 110 The removable seat (Fig. 10) consists of a circular disk with a central aperture surrounded, on both sides of the disk, by a circular rib or bead, a', which is adapted to receive the rubber valve upon the lower end of 115 the valve stem when the latter is forced downward to its seat. The rubber valve upon the lower end of the valve stem may be readily removed when it becomes worn and replaced with another, and the metal disk 120 may be reversed when the raised seat upon one side of it becomes worn, and removed and replaced with a new one when both sides become worn.

In Figs. 11 and 12 I have shown my improved valve suitably modified to adapt it for use as a top supply valve, secured to the upper edge of the flushing tank, instead of being secured in the bottom of the tank as in the main views. To this end the casing of 130

the valve is provided with a projecting supporting arm or plate O adapted to fit upon the upper edge of one wall of the tank and be secured thereto with screws. The valve 5 stem and valve in this construction are inverted, Fig. 12, the valve closing against its seat by an upward movement instead of a downward one. The operating rod C and its crank C' are substantially the same as in the 10 main views, excepting that the crank in the angular bent end of the rod is bent toward the free end of the rod, instead of in the opposite direction as in the main views, in order that the lifting of the free end of the rod will 15 serve to lift the valve and force it against its seat. A removable metal seat, similar to that shown in Figs. 9 and 10, fits within the upper end of the tubular casing and rests upon an annular shoulder formed therein to receive 20 it, and the end of the casing is exteriorly threaded to receive a coupling nut P by which an angular pipe connection or tail-piece Q is coupled to the casing, a tight joint 25 between the upper surface of the removable valve seat and the flanged lower end of the nozzle Q, within the coupling nut, being secured by a rubber gasket R. Secured in the 30 lower end of the valve casing A is an extension A', commonly called the "hush-pipe", which extends downward nearly to the bottom of the tank and delivers the water at that point.

It will of course be understood that the metal valve and rubber seat of Figs. 1 to 6 35 may be employed in the valve of Figs. 11 and 12, if desired, instead of the rubber valve and metal seat of Figs. 9 and 10.

Having thus fully described my invention, I claim:

40 1. In a ball-cock valve, the combination, with the valve casing and valve, of a valve-operating rod formed at one end into a crank having bearings in opposite sides of the valve casing and coöperating with the valve said 45 crank end of the rod being arranged to be inserted through said bearings; substantially as described.

2. In a ball-cock valve, the combination, with the valve casing and valve, of a valve 50 operating rod formed at one end into a crank having bearings in opposite sides of the valve casing and coöperating with the valve, said crank end of the rod being arranged to be inserted through said bearings and withdrawable from engagement with the valve 55 only when the rod is swung to an inoperative position; substantially as described.

3. In a ball-cock valve, the combination, with the valve casing and valve, of a valve 60 operating rod formed at one end into a crank having bearings in the valve casing and coöperating with the valve, and locking means operating to prevent accidental displacement of the crank from its bearings while the rod is

in operative position and to permit its withdrawal therefrom when the rod is swung out of operative position; substantially as described. 65

4. In a ball-cock valve, the combination of a tubular valve casing, a longitudinally moving valve stem and valve therein, a 70 valve-operating rod formed at one end and intermediate its length into a crank detachably connected with the valve stem and having bearings in the valve casing on either side of the crank, said crank end of the rod being 75 insertable through said bearings, and means for locking the valve stem and crank together except when the rod is swung to an inoperative position; substantially as described. 80

5. In a ball-cock valve, the combination of the tubular valve casing, the longitudinally movable valve stem and valve therein, the valve-operating rod formed at one end into a crank having bearings in the valve 85 casing and coöperating with the valve stem, and locking means preventing accidental displacement of the crank while the rod is in operative position but permitting the withdrawal of the crank when the rod is swung 90 out of operative position; substantially as described.

6. In a ball-cock valve, the combination of the tubular valve casing, the longitudinally moving valve stem and valve therein, 95 the valve operating rod formed at one end into a crank having bearings in the valve casing and coöperating with the valve with which it is detachably connected, and a locking lug upon the wall of the valve casing co-operating with said crank portion of the operating rod to prevent displacement of it only while the operating rod is in operative position; substantially as described.

7. In a ball-cock valve, the combination 105 of the tubular valve casing provided at its upper end with a flange adapted to seat against the bottom of the tank and a cap or hood forming a lateral discharge outlet for the casing, the longitudinally moving valve stem within the valve casing, carrying the valve at its lower end, and the valve-operating rod formed at one end into a crank having bearings in the cap or hood of the casing and coöperating with the upper end of the 110 valve stem; substantially as described.

8. In a ball cock valve, the combination of the tubular valve casing provided at its upper end with a flange adapted to seat against the bottom of the tank and a cap or hood forming a lateral discharge outlet for the casing, the longitudinally moving valve stem within the valve casing, carrying the valve at its lower end, the valve-operating rod formed at one end into a crank having bearings in the 115 cap or hood of the casing and coöperating with the upper end of the valve stem, and a locking lug upon the side wall of said cap or 120

125

hood coöperating with the crank to prevent displacement of the latter while the operating rod is in operative position; substantially as described.

5 9. In a ball-cock valve, the combination of the tubular casing A provided with the internal longitudinal guide ways, the longitudinally moving valve stem H guided in said ways within the casing and carrying a valve 10 at one end, and the operating rod C provided intermediate its length with the crank C having its bearings in the valve casing and engaging a recess in the end of the valve stem opposite the valve, for operating the latter 15 said crank being detachable from the valve stem only in the inoperative position of such rod; substantially as described.

10 10. In a ball cock valve the combination of the tubular casing A having the exteriorly 20 threaded lower end and provided at its upper end with the flange F and cap or hood B, the valve stem H located within the tubular casing A and guided longitudinally in ways formed therein and carrying the valve at its 25 lower end and projecting at its upper end into the cap or hood B, the nut G screwed upon the threaded body of the valve casing and adapted to coöperate with the flange F to secure the casing in position, and the operating rod C provided with the crank C' having 30 its bearings in the cap or hood B of the casing and engaging a recess in the upper end of the valve stem to operate the valve; substantially as described.

35 11. In a ball cock valve, the combination of the tubular casing A having the exteriorly threaded body portion and provided at its upper end with the flange F and cap or hood B, the nut screwed upon the threaded body 40 of the valve and adapted to coöperate with the flange F to hold the casing in position, the valve stem H guided longitudinally within the casing A and carrying the valve I at its lower end and projecting at its upper end 45 into the cap or hood B, the pipe section K secured to the lower end of the casing A by the coupling nut L screwed upon the threaded end of said casing, the valve seat within said coupling nut coöperating with the valve I, and 50 the operating rod C carrying the ball or float at its free end and formed at its opposite end into a crank having its bearings in the cap or hood B and engaging a recess in the upper end of the valve stem to operate the valve; substantially 55 as described.

12. In a ball cock valve, the combination of the valve stem H carrying the valve I at one end and provided at its opposite end with a recess open at one side only, an operating rod C carrying a float at one end and formed at its other end into a crank which engages said recess in the valve stem, said 60 casing having in its opposite sides bearings for said crank, and means for preventing the 65 disengagement of the rod and valve stem

except when such rod is swung to an inoperative position; substantially as described.

13. In a ball-cock valve, the combination of a valve casing, a valve therein, an operating rod adapted to carry the ball or float at 70 one end and having its opposite or inner end bent at right angles to its body portion, said inner end of the rod bearing in opposite sides of the casing and formed into a crank adapted to operate the valve; substantially 75 as described.

14. The combination with the valve casing having the bearing apertures in its opposite side walls and the recess d adjacent one of said apertures, of the operating rod C provided at one end with the crank C' having its 80 bearings in said apertures and the insertion and withdrawal thereof being permitted by said recess d; substantially as described.

15. The combination, with the valve cas- 85 ing provided with the opposite bearing apertures and the recess d and locking lug e adjacent to one of said apertures, of the operating rod C provided at one end with the crank C' having its bearings in said apertures 90 and locked in operative position therein by the lug e and permitted to be withdrawn, when swung out of operative position, by the recess d; substantially as described.

16. In a ball cock valve, the combination, 95 with a tank, of a valve casing in constant communication therewith and connected to a source of supply, a valve in said casing, and a valve-operating rod connected at its outer end to the ball or float and formed at its 100 other end into a crank having bearings in the valve casing and coöperating with the valve, substantially as described.

17. In a ball cock valve, the combination with the valve casing, of a valve arranged 105 therein and having a stem formed at its free end into a hook, a valve-operating rod formed at one end into a crank and bearing in opposite sides or walls of the casing, said crank engaging said hook of the valve stem, and 110 means for maintaining such engagement of the valve stem and crank during the range of operative movements of the rod, but permitting disengagement when the rod is swung to inoperative position, substantially 115 as described.

18. In a ball cock valve, the combination of a tubular valve casing provided at one end with a cap or hood forming a lateral discharge outlet, the longitudinally moving 120 valve stem arranged within the valve casing and carrying a valve at its lower end, and the valve-operating rod formed at one end into a crank having bearings in said cap or hood and coöperating with the upper end of the 125 valve stem, substantially as described.
